UNITED STATES PATENT OFFICE.

THOMAS C. DEVLIN, OF PORTLAND, OREGON, ASSIGNOR OF ONE-HALF TO
D. SOLIS COHEN AND SIGEL GRUTZE, OF SAME PLACE.

STAMP-ATTACHING AND SEALING MACHINE.

SPECIFICATION forming part of Letters Patent No. 543,440, dated July 23, 1895.

Application filed April 25, 1894. Serial No. 508,929. (No model.)

To all whom it may concern:

Be it known that I, THOMAS C. DEVLIN, of Portland, in the county of Multnomah, State of Oregon, have invented certain new and useful Improvements in Stamp-Attaching and Sealing Machines, of which the following is a full, clear, and exact specification.

This invention relates to machines for affixing postage or other stamps to envelopes or packages, and has for its object to provide an automatic and perfectly-operating device of this character, through the agency of which the stamp may be cut from a sheet or strip, moistened, and secured upon the envelope at the proper corner or upon any other desired portion thereof by the mere movement of one single rod or lever.

The invention consists in the novel construction and arrangement of parts herein-after fully described and set forth in particularity.

In the accompanying drawings, forming part of this specification, in which like letters of reference designate corresponding parts in all the views, Figure 1 is a vertical longitudinal section of my invention taken upon a line corresponding to xx in Fig. 2. Fig. 2 is a horizontal section upon the line yy , Fig. 1, the reel, clutch-arm, and spring, forming a part of the invention, being shown in plan. Fig. 3 is a transverse section upon the line zz , Fig. 2. Fig. 4 is a front elevation. Fig. 5 is an inverted plan view, illustrating in detail the rollers through which the stamps pass.

In the practice of my invention I construct a base-piece A of suitable size, shape, and material, having formed near the edge, upon the rear and the two sides thereof, a shoulder or support B. At the front of the said base-piece, somewhat removed from its edge, is an upright or wall C projecting outwardly from a point below the middle to the top thereof and formed, as shown in Fig. 1, of two sectionally inverted L-shaped pieces of metal.

Resting upon the shoulders B and extending through or abutting against the lower portion of the front wall C is a flooring D, which, serving as a support for the entire mechanism, or a majority thereof, is preferably formed of metal. From the top of the front wall C to the shoulder B is a rectangular casing inclos-

ing the whole of the device on all three sides. This casing may be formed in two or more pieces and be suitably hinged at the top, as indicated, to enable access to be had to the various parts of the machine.

Toward the rear of the device is a reel or spool F, journaled in one side of the casing E and in a bearing a secured upon the flooring D, this reel being rotatable by a crank b , and having wound thereon the postage-stamps d , which it will be understood are arranged in a strip or sheet. Resting upon the reel F are weight-rollers c , serving to prevent too free revolution of the said reel and to maintain a regular and even tension of the strip of stamps d wound thereon, these weight-rollers being supported by a bar e pivoted in the casing.

Immediately in front of the reel F is a guide-roller f , journaled in the bearing f' upon the flooring D and also in the side of the casing E. Beyond this guide-roller f and slightly to the rear of the front wall C are feed-rollers g , h , and h' , intervening which and the guide-roller f are guide-pieces i.

The upper feed-roller g is mounted upon the journal j , extending from side to side of the casing, in which it works, and having thereon at each end the corrugations or teeth g' , which said teeth are comparatively fine or narrow, but which may be omitted altogether and the surface of the roller be roughened in any other desired manner. At the outside of the casing the journal j has thereon the milled head or handle g^2 , by means of which the roller g may be turned and the stamps fed forward. The lower feed-rollers h h' , which lie below the plane of the floor D, are mounted to turn upon an axle j' , loosely resting in supports h^2 upon the under side of the said floor, the said rollers being revoluble independently of each other.

Rearward of the feed-rollers is a spring-arm k , secured to the floor D by a screw k' and having at the end thereof the grooved head or yoke l , which clasps the axle j' at the under side thereof and serves to maintain the feed-rollers h h' normally in engagement with the roller g , yet permitting them to move slightly to either side, to operate in conjunction with the roller g and prevent crushing of the stamps to one side. This spring-arm is adjustable

by means of the screw k^2 , which thus regulates the pressure of the rollers. Above this spring-arm k and journaled in bearings m' is a cam-shaft m , having a crank or handle m^2 5 on the end thereof outside of the casing, whereby the said cam-shaft may be turned to force the arm k downward and release the rollers h h' from contact with the roller g to permit removal of the stamps.

Upon the journal j , on which the roller g is secured, is mounted the spur-gear n , meshing with the gear-wheel G , which is journaled in the casing above the said roller g . Within this gear-wheel is secured a drum H , and upon 15 the same journal as that on which the said drum and gear-wheel are mounted is a friction-clutch H' , which is adapted to engage with the said drum only upon its forward movement. Any form of friction-clutch capable of effecting this end may be used, the device herein shown being a counterpart of the well-known clutch of the Howe sewing machine. The said clutch H' is normally held in engagement with the drum H by means of 25 a spring H^2 . The arm I of this clutch, which extends upwardly therefrom, has a slot I' therein and is connected at the top thereof by means of a spiral spring J to a hook a' at the top of the post or bearing a , in which the reel 30 or spool F rests, the tendency of the said spring being to contract.

Extending through the slot I' in the clutch-arm is a shoulder-pin o , screw-threaded and having thereon the thumb-nut o' , by means 35 of which it may be secured in the slot at any point thereof. This point passes through the end of a connecting-rod K , which said rod is pivoted to the lower end of a lever L , journaled at the center or at any other desired 40 point in the casing, and having at the top thereof a friction-roller L' .

To the journal L^2 , on which the lever L is mounted, is secured an arm M , having in the head thereof, which said head is oblong in 45 shape, an elongated groove M' . The said arm M has attached thereto, by means of an adjustable pin M^2 extending through the slot M' , a plate N , which bears upon the flexible air-bulb o of an atomizer, the air-nozzle o' of 50 which passes through and is secured to a bracket P . The height and position of this bracket is regulated by screws p . From the nozzle O' depends a pipe q , the nozzle o' passing through the flooring D and through the 55 front wall C , where its outlet-orifice is arranged in operative relation to the discharge-opening of a water-pipe r , which connects with a reservoir Q adjoining the casing E at the base A . It will be understood that this 60 pipe r is so connected to the reservoir (see Fig. 3) as to be constantly kept filled with water by the reservoir Q , which itself is replenished through the aperture Q' in the top thereof, and that upon pressing the bulb O 65 air will be forced through the pipe q , expelling and spraying the water in the pipe r upon the envelope beneath.

Upon the exterior of the front wall C is secured a plate s , having on the face thereof an outer plate t of hardened steel, both of the 70 said plates and the wall C having thereon slots s' aligning with each other and with the feed-rollers g and h h' at their points of engagement. The plate s is rabbeted at the bottom for the entrance of the pipes q and r , 75 hereinbefore referred to. Within the projecting portion of the wall C is held a vertically-movable rod R , preferably square in shape to prevent turning, the said rod having at the top thereof a knob or handle R' , and 80 being surrounded at the interior by a spiral spring S secured to the said rod by a pin S' . At the rear of the rod, near the center thereof, is affixed a block T , beveled at the bottom, and having upon the top thereof a spring T' , 85 which bears upon the under side of the wall C .

Upon the lower end of the rod R is mounted a metallic block u , which may, if desired, be provided with yielding material u' upon its under surface, and having at the rear thereof 90 the sharpened steel knife-blade v . This blade v is provided with an inclined edge to facilitate the cutting operation in accordance with the well-known principle, and the block u is similarly formed to correspond therewith, as 95 shown in Fig. 4 of the drawings.

Upon the base-piece, immediately in front of the slot s' , is placed a slab or block U , inclined to correspond with the block u , and having thereon a rubber covering or surface 100 U' . This slab is not permanently secured to the base-piece, and may be removed therefrom when bulky packages are to be stamped.

The operation of the device will be readily understood from the foregoing description, 105 taken in connection with the drawings.

The stamps d having first been wound upon the reel F , the end thereof inserted between the feed-rollers g , h , and h' , and fed forward by turning the roller g through the agency of 110 the milled head g^2 , the envelope or other package to be stamped is placed upon the slab U , the rod R is depressed by means of the knob R' , the block T thereon engaging with the friction-roller L' and pressing the top of the 115 lever L rearwardly. As this is done the plate N presses the bulb O , which causes the water present in the pipe r to be sprayed upon the surface of the envelope immediately adjacent to the said pipe, and as the rod R is depressed the lever L will be further forced 120 rearwardly, thereby bringing the clutch-arm I forward and turning the gear-wheel G , which, by means of the gear N , actuates the feed-roller g , and the strip of stamps d is fed forward a sufficient length to cause the protrusion of one stamp beyond the plate t . By the time this has been effected the beveled or tapered portion of the block T will have passed 125 the friction-roller L' , and as the remaining portion of the said block is perpendicular the rod R will continue to descend without further actuating the mechanism, and the blade v at the rear of the plate u will engage with 130

the plate *t*, and acting in conjunction therewith will shear off one stamp from the strip *d*, which said stamp will fall upon the envelope at the moistened portion thereof, and when the plate *u* is pressed downwardly upon the envelope lying upon the slab *U*, the said stamp will be affixed to the said envelope. The knob *R'* being released, the rod *R* will be raised upwardly by the spiral spring *S*, and the spiral spring *J* connecting the clutch-arm *I* with the post *a* will cause the different parts to resume their former positions, the gear-wheel *G* and the feed-rollers, however, not being affected, as the clutch *H'*, as before stated, is incapable of turning the drum *H* and the gear-wheel *G* other than on the forward movement thereof. This prevents the stamps from being fed backwardly on the recoil of the rod *R*.

In conjunction with the stamp-affixing device hereinbefore described, I have designed an attachment for sealing the flaps of the envelopes to be stamped, which said device comprises a tube *V* inserted in the reservoir *Q*, perforated at the bottom and having therein a wick, sponge, or other absorbent material *W*, above which is secured a cap *w* which serves as a guide for the envelope-flap and presses the same downward in engagement with the sponge.

It will be observed that the spraying of the water may be increased or decreased in quantity and rapidity by the adjustment of the bracket *P* to raise or lower the position of the bulb *O*, with reference to the plate *N*, or the said plate *N* may itself be adjusted by means of the screw-pin *M'* which secures the shank of the said plate in the groove *M*. It will also be possible to readily regulate the feed of the rollers *g* *h* and *h'* by raising or lowering in the groove *I'* the pin *o* which secures the connecting-rod *K* to the clutch-arm *I*, the point of junction thereof being prearranged according to the length, or if it is desired to feed the stamps laterally, according to the width of the stamps used.

I desire it to be understood that I do not confine myself to the use of all the different parts herein illustrated nor to the exact details of mechanism set forth, as the same may be changed or varied and in some instances altogether omitted, as convenience may dictate.

Having thus fully described my invention, what I claim as new, and desire to secure by Letters Patent, is—

1. A device of the class described comprising a stamp receptacle, means for feeding the stamps therefrom, a presser acting to affix the stamps, an atomizer arranged to contribute moisture, and a lever in operative relation to the presser and having an extension to operate the atomizer.

2. A device of the class described comprising a stamp receptacle, means for feeding the stamps therefrom, a presser acting to affix the stamps, an atomizer having an air bulb and

arranged to contribute moisture, a projection on the presser, and a lever in the path of the said projection, said lever having operative connection with the feeding mechanism and the atomizer.

3. A device of the class described comprising a stamp receptacle, means for feeding the stamps therefrom, a presser acting to affix the stamps, an atomizer arranged to contribute moisture, a lever in operative relation to the presser and having an extension to operate the atomizer, and means for rendering the feed mechanism inoperative at times.

4. A device of the class described comprising a stamp receptacle, means for feeding the stamps therefrom, a presser acting to affix the stamps, an atomizer having an air bulb and arranged to contribute moisture, a projection on the presser, a lever in the path of the said presser, said lever having operative connection with the feeding mechanism and the atomizer, and means for rendering the feed mechanism inoperative at times.

5. A stamp affixing machine comprising a reel, feed-rollers delivering through a slot in the frame of the device, a slotted metallic plate secured over the said slot in the frame, a spring-controlled actuating rod having a beveled block thereon, a lever pivoted adjacent to the said rod and adapted to be operated by the said block, an atomizer arranged near the said lever, a plate connecting with the lever and adapted to operate the atomizer, a connecting rod joining the lever to the arm of a clutch engaging with a gear-wheel, which meshes with a gear upon one of the feed-rollers, in such manner as to turn the same in but one direction, pipes leading from the air bulb of the atomizer, and from the water reservoir, to a point in front of the stamp feed, and a pressing block upon the lower end of the said rod having a cutter blade thereon, substantially as shown and described.

6. A stamp affixing machine comprising a reel, feed-rollers delivering through a slot in the frame of the device, guides intervening the reel and the feed-rollers, a slotted metallic plate secured over the said slot in the frame, a vertically movable spring-controlled actuating rod carrying a block beveled at the lower portion thereof, a lever pivoted adjacent to the said rod and adapted to be operated by the said block, an atomizer supported upon a bracket near the said lever, a plate secured to an arm connecting with the said lever and adapted to operate the said atomizer, a connecting rod joining the said lever to the arm of a clutch engaging with a gear-wheel, which meshes with a gear upon one of the feed-rollers, in such manner as to turn the same only upon the downward movement of the said rod, the said connecting rod being adjustably secured to the said clutch arm, pipes leading from the air bulb of the atomizer and from a water reservoir to a point in front of the stamp feed, the said pipes being arranged to spray a portion of the envelope.

- or package to be stamped, and a pressing block upon the lower end of the rod, having a sharpened cutter blade thereon, substantially as shown and described.
5. A device of the class described comprising a stamp receptacle, means comprising rolls for feeding the stamps therefrom, a presser acting to affix the stamps, an atomizer having an air bulb and arranged to contribute moisture, a projection on the presser, a lever in the path of the said presser, said lever having operative connection with the feeding mechanism and the atomizer, and means for separating the feed rolls at times to prevent feeding of the stamps.
10. A device of the class described comprising a stamp receptacle, means comprising

rolls for feeding the stamps therefrom, a presser acting to affix the stamps, an atomizer having an air bulb and arranged to contribute moisture, a projection on the presser, a lever in the path of the said presser, said lever having operative connection with the feeding mechanism and the atomizer, and means for separating the feed rolls at times to prevent feeding of the stamps.

In testimony that I claim the foregoing as my invention I have signed my name, in presence of two witnesses, this 19th day of April, 1894.

THOMAS C. DEVLIN.
